(57) **CLAIM**

The ornamental design for a pump body of an inflatable penile prosthesis, as shown and described.

DESCRIPTION

FIG. 1 is an isometric view of one embodiment of a design for a pump body of an inflatable penile prosthesis.

FIG. 2 is a front side view thereof.

FIG. 3 is a back side view thereof.

FIG. 4 is a top side view thereof.

FIG. 5 is a bottom side view thereof.

FIG. 6 is a left side view thereof; and,

FIG. 7 is a right side view thereof.

The broken lines in the Figures form no part of the claimed design.
